UNITED STATES PATENT OFFICE.

WILLIAM CULVER, OF SIOUX CITY, IOWA, ASSIGNOR OF ONE-HALF TO WENCER H. KIRCHMAN, OF WAHOO, NEBRASKA.

DIRIGIBLE BALLOON.

1,276,497.

Specification of Letters Patent. Patented Aug. 20, 1918.

Application filed July 18, 1917. Serial No. 181,271.

To all whom it may concern:

Be it known that I, WILLIAM CULVER, a citizen of the United States, residing at Sioux City, in the county of Woodbury and State of Iowa, have invented certain new and useful Improvements in Dirigible Balloons, of which the following is a specification.

This invention relates to improvements in aerial travel or navigation, generally, more especially balloons of the dirigible type, or similar contrivances.

The invention has for its object, primarily, to provide for using the exhaust, particularly, from gasoline-engines for effecting the raising of the dirigible or balloon, with the ultimate end in view of rendering aerial navigation or travel with perfect safety.

Other objects of the invention will appear in the further disclosure thereof.

The invention consists of certain instrumentalities and features of construction substantially as hereinafter fully disclosed by the description and illustration in connection with the appended claim.

In the accompanying drawing is illustrated the preferred embodiment of my invention wherein it will be understood that various changes or modifications may be made as to the details of construction and arrangement of the parts, and in which drawing—

Figure 1 is a side elevation of my improved aerial travel or navigation device, the dirigible or balloon being omitted.

Fig. 2 is a central vertical transverse section of the same.

Fig. 3 is an inverted view thereof.

Fig. 4 is a fragmental perspective view of the device showing more particularly the swinging wings or planes and their actuating pitman, upon an enlarged scale.

Fig. 5 is a sectional view of the dirigible with adjustive parts shown fragmentally.

Fig. 6 is a fragmental and partly sectional and partly perspective view of the same.

In carrying out my invention I provide for carrying the usual platform 1, opposed preferably arcuate frames 2 suitably secured to the platform and also having positioned therebetween the dirigible container or bag 3. The latter has secured therein staggeredly arranged baffles 4 for

suitably distributing the inflating gas or exhaust delivered thereto, said bag or dirigible having a gas or exhaust intake or filling tube 5 leading to the exhaust-pipe of the gasoline-engine or other source to receive gas or exhaust, as the case may be.

Depending below the gasoline engine presently more fully described, is an air chamber 6 to serve for flotation in event of the device alighting or dropping in a body of water, said air chamber being positioned intermediate of the carrying wheels 7 suitably guarded by guide or trundle-rolls 8, taking part of the weight off the latter.

Suitably supported or suspended from the platform-supporting frame members 2, by means of suspenders 9, is a gasoline engine 10, of ordinary or approved type and, from the gasoline engine, leads an exhaust pipe 11, having valved pipe-connection, as at 12, with the intake pipe 5 of the dirigible or bag 3, for delivering the exhaust through said pipes 5, 11, into said bag or dirigible for suitably inflating the latter, the valve 12 providing for enabling the operator to regulate the amount of gas or exhaust it may be desired to supply to said bag or dirigible as circumstances may call for.

Interiorly of the dirigible or balloon is applied a wire "screening" or fabric 12^a which is laced to the inside of the hoops, and inside of this wire fabric or "screening" is applied preferably, by gluing, a gas-proof fabric 12^b, and upon the outside of the hoops is laced a weather proof fabric 12^c, this arrangement or structure providing a much cheaper covering than that now in general use while equally durable.

The gasoline engine is provided with pluralities of swinging wings or planes 13, 14, suitably pivoted in position and whose actuating crank-shafts are connected by pitmen 16 thereto for imparting the requisite swinging or reciprocating motion to said wings or planes, as in effecting the aerial propulsion or travel of the machine, said crank-shafts being, of course, driven in the usual way, from the machine or engine 10. The engine or machine, in practice, is operated in connection, preferably, with twin cylinders, such as are used in a motor-cycle, with a self starter attached thereto. The engine, it will be understood does not, as has been disclosed, run or operate ordinary propeller-wheels, but oper-

ates propelling or swinging wings or planes, 13, 14, which are provided with hinged doors or valves self-opening upon the return stroke of said planes, letting air therethrough and lessening resistance, but which valves close, practically converting the planes into a solid piece, upon the outward stroke, respectively, and vice-versa.

5 A valved pipe connection 17 between the bag or dirigible 3 and the engine 10 is provided to exhaust the engine-exhaust from said bag or dirigible, as when the valved connection 12 is closed and it may be desired to withdraw the exhaust from said bag 10 or dirigible.

10 It will be understood that the two series of swinging planes or wings are adapted to exert a pulling and a pushing action, respectively in the propulsion of the machine or engine, whereby the load is evenly distributed upon the engine at all times. It is also observed that the lateral planes or wings will be similar to those of a conventional type of air-planes and provide for 15 gliding or guiding the machine up and down, while the front and back wings or planes, such also being provided as at 13^a, provides for steering the machine from side to side or laterally, the engine or machine 20 thus being held under perfect control as against accident or casualty.

By suitably manipulating the valves of the bag-tube of the balloon and of the exhaust, the gas will be admitted to said bag. When it may be desired to exhaust the gas 35 or deflate the bag all that is required is to stop the engine and open both valves. If it be desired to rise only a certain distance, but to keep going ahead, the bag-controlling valve is closed and the exhaust expelled into 40 the air.

I claim—

A device of the type described, including an engine of the class indicated, in combination with a dirigible balloon or bag, said 45 bag having its intake tube, and said engine having its exhaust pipe in valved communication, a gas exhausting pipe for said bag, having connection with said valve-controlled engine exhaust-pipe and bag-exhaust-intake pipe, and propelling means for said balloon or bag driven from said engine, said bag-gas-exhausting pipe adapted to be operative when the said bag gas-intake pipe is out of valved communication 50 with said bag.

In testimony whereof I affix my signature in the presence of two witnesses.

WILLIAM CULVER.
